UNITED STATES PATENT OFFICE

1,924,526

CAPACITY INCREASING MEANS FOR
COUNTING WHEELSBruce H. Tingley, Dayton, Ohio, assignor to
Ohmer Fare Register Company, Dayton, Ohio

Application September 9, 1927. Serial No. 218,457

9 Claims. (Cl. 235—30)

This invention relates to a novel means for increasing the capacity of a 5¢ taximeter from \$9.95 to \$19.95 without making the machine larger, which would be necessitated if another 5 drum were added.

In the drawing, Fig. 1 is a fragmentary front elevational view,

Fig. 2 is a cross-sectional view thereof, and Fig. 3 is a top plan view thereof.

10 This invention is an improvement on a taximeter of the type shown in the patent to J. F. Ohmer and E. H. Bridenbaugh 1,136,164, patented August 20, 1915. In the said patent, the flag shaft 320 is controlled by the operator.

15 The shaft 15 is a rocking shaft which is actuated by either a moving part of the vehicle or a clock, which rocking shaft 15 carries an arm 14 to which is pivoted a pawl 13, a spring 13b serving to hold the arm 13a of the pawl 13

20 against a stop 14a. The pawl 13 engages a ratchet 12 and operates the same step by step. The ratchet 12 is mounted on a shaft 9 and is operatively connected with the units fare indicating wheel 1, which units wheel is operatively

25 connected to and drives the 10¢ wheel 2 and \$1.00 wheel 3. The connection between the wheels 1, 2 and 3 is conventional and is clearly set forth in the said patent. The units wheel 1 is provided with five sets of numerals, each

30 of which set is zero and five, so that these numerals will appear on the circumference thereof in alternation. The 10¢ wheel 2 and the \$1.00 wheel 3 are each provided with numerals zero to nine inclusive.

35 The indicator wheels 1, 2 and 3 are operatively connected with gears 4, 5 and 6 respectively, which gears mesh with gears 7, 8 and 10 mounted on a shaft 99. The gears 7, 8 and 10 have secured thereto type wheels 11, 16 and 17,

40 which type wheels have printing characters thereon corresponding to the numerals which would appear on the indicating wheels 1, 2 and 3. These type wheels print on the ticket which is delivered to the passenger when he is dis-

45 charged from the taxicab, as clearly set forth in the above mentioned patent.

The gears 4, 5 and 6 drive gears 18, 19 and 20 on a shaft 109, which gears are secured to printing wheels 21, 22 and 23 having type thereon to print on a record as is fully set forth in the above mentioned patent. All of the structure thus far indicated is shown in the said patent.

It is obvious that with such a construction 55 the maximum amount that could be registered

on the three indicating drums 1, 2 and 3 or on the two groups of printing wheels would be \$9.95. It is sometimes found that the fare runs to more than that amount. Additional printing wheels could be inserted to register more than 60 \$9.95 but this would necessitate increasing the size of the taximeter, whereas the modern tendency is to decrease the size of the taximeter as much as possible. This invention, therefore, relates to a novel means whereby the desired results can be obtained without the necessity of increasing the size of the taximeter and without installing a fourth indicating wheel and a fourth printing wheel.

To obtain this advantage I provide a cam 24 70 on the flag shaft 320. When the flag is in vacant position the parts will be as indicated in Fig. 2. In that position the cam 24 engages a three-armed lever 25 mounted on the shaft 26. One arm 27 of the lever is provided with an outstanding ear 28 which engages the end of a lever 29 rotatably mounted on the rocking shaft 15. The lever 29 is provided with an arm 30 to which is secured a spring 31 attached to the framework of the taximeter. The spring 31 75 tends to rotate the arm 30 in a counter-clockwise direction so as to hold the nose 32 of the lever 29 against the periphery of a disk 33 carried by the gear 10 which is secured to the printing wheel 17. The disk 33 is provided 80 with a cam 34.

A yoke 35 is loosely mounted on the shaft 99 which yoke extends over an arm 36 and the lever 25 and is provided with an extension 47 which carries the printing character "1" at the end 90 thereof. The yoke 35 is connected to a reciprocating link 37 by means of a pin 38. The link 37 has a forwardly extending arm 39 which carries an indicating character "1" on a plate 40. The lower end of the link 37 is connected to a 95 yoke 41 by means of a pin 42. The yoke 41 is loosely mounted on the shaft 109 and carries a printing character 43 at the end thereof. The link 37 is normally held in a depressed position by means of a spring 44.

In operation the parts are held in the position shown in Fig. 2 when the flag is in for hire position, the parts being so held by the cam 24 engaging the lever 25 so that the arm 36 holds the forward end of the yoke 35 in a raised 105 position. The printing type carried by the extension 47 is held below the printing position and the printing type 43 is held above the printing position while the indicating plate 40 is held in a raised position so that it can not be read. 110

When the flag is thrown to a tariff position the cam 24 is rotated away from the lever 25 but the lever is not free to move for the reason that the ear 28 of the arm 27 engages the lever 29. It is true that the spring 44 would tend to lower the link 37 but to do this it would be necessary for the lever 25 to rotate it in a counter-clockwise direction, which it cannot do. When the \$1.00 printing wheel 17 is rotated beyond the point 10 where the numeral 9 would be in printing position, the cam 34 engages the nose 32 of the lever 29, partially rotating the lever in a clockwise direction against the tension of the spring 31 so that the forward end of the lever 29 is 15 depressed beneath the ear 28 thereby permitting the lever 25 to rotate. The spring 44 immediately pulls the link 37 downwardly and moves the printing type on the extension 47 into printing position and simultaneously moves the printing 20 character 43 into printing position as well as the plate 40 into a position where it can be read. The parts would remain in this position until the meter was reset. The fare printing wheels and indicating wheels could continue their rotation 25 beyond the \$10.00 designation without in any wise interfering with the position of the indicating and printing characters "1".

When the machine was reset the various type and indicating wheels would be reset in the conventional manner and the cam 24 would engage 30 the lever 25 rotating it clockwise so that the ear 28 would engage the lever 29 and the arm 36 would elevate the link 37, moving the printing characters and the indicating characters out of 35 printing and indicating positions.

It is readily perceived that instead of raising the link 37 it could be lowered and the same results would be obtained. Furthermore, the lever 25 might be eliminated altogether by coupling 40 the yoke 35 with the arm 29. Other changes might be made without departing from the spirit of this invention. I, therefore, desire to claim the invention broadly in whatever form it may be embodied which may fairly fall within 45 the scope of the present invention.

I do not desire to limit my invention to a taximeter as it can be used to advantage in other machines, such as cash registers, fare registers and the like.

50 I claim:

1. In a machine, a group of counting wheels, a cam operatively connected to the wheel of the highest order, a lever actuated by said cam, a bell crank lever normally held against movement 55 by said first mentioned lever, a plate provided with a numeral, said second mentioned lever normally holding said plate against movement, said cam rocking said first mentioned lever and releasing it from said second mentioned lever 60 when the wheel of highest order is rotated beyond a certain point and means operative to actuate said plate when said first lever releases said second lever.

2. In a machine, a group of digit wheels, a 65 disk carried by the digit wheel of highest order, a cam on said disk, a three-armed lever, one arm of which lies in the path of movement of said cam when the wheel of highest order is rotated beyond a given point, a spring connected 70 to the second arm of said lever and normally holding the first mentioned arm of said lever against the periphery of said disk, a second lever having an arm normally engaged by the third arm of said first mentioned lever but adapted 75 to be released therefrom when said cam rocks

said first mentioned lever, a third lever provided with a digit which lever is normally held by said second mentioned lever so that the digit on the third mentioned lever is out of alignment with the digits on said wheels and means whereby the digit on the third mentioned lever is raised into alignment with the operative digits on said wheels when said cam rocks said first mentioned lever.

3. In a machine, a group of digit wheels, a disk carried by the digit wheel of highest order, a cam on said disk, a three-armed lever, one arm of which lies in the path of movement of said cam when the wheel of highest order is rotated beyond a given point, a spring connected to the second arm of said lever and normally holding the first mentioned arm of said lever against the periphery of said disk, a second lever having an arm normally engaged by the third arm of said first mentioned lever but adapted to be released therefrom when said cam rocks said first mentioned lever, a third lever provided with a digit which lever is normally held by said second mentioned lever so that the digit on the third mentioned lever is out of alignment with the digits on said wheels and means whereby the digit on the third mentioned lever is raised into alignment with the operative digits on said wheels when said cam rocks said first mentioned lever and means whereby all of said levers may be reset.

4. In a machine, a set of indicating wheels, a set of printing wheels, plates, each of which has a numeral thereon which may be brought into alignment with the operative digits on said wheels, a shaft on which one of the sets of wheels is mounted, a lever pivoted on said shaft and carrying one of said plates, an arm pivoted to said lever and carrying the other of said plates and means whereby said plates may be moved into alignment with the operative digits on said wheels whereby the capacity of said machine may be increased to an amount greater than the capacity of said wheels.

5. In a machine, a set of indicating wheels, a set of printing wheels, plates, each of which has a numeral thereon which may be brought into alignment with the operative digits on said wheels, a shaft on which one of the sets of wheels is mounted, a lever pivoted on said shaft and carrying one of said plates, an arm pivoted to said lever and carrying the other of said plates and means whereby said plates may be moved into alignment with the operative digits on said wheels whereby the capacity of said machine may be increased to an amount greater than the capacity of said wheels, and means whereby said plates may be reset.

6. In a machine, a set of indicating wheels, a plurality of sets of printing wheels, shafts on which each of said sets of wheels are mounted, a lever pivoted on each of the shafts of the printing wheels, a plate provided with a digit carried by each of said levers, a link connecting each of said levers, an arm carried by said link, a plate provided with a digit carried by said arm and means whereby each of said plates may be moved into alignment with the operative digits of its associated set of wheels when one of the wheels of highest order passes a predetermined point.

7. In a machine, a set of indicating wheels, a plurality of sets of printing wheels, shafts on which each of said sets of wheels are mounted, a lever pivoted on each of the shafts of the

printing wheels, a plate provided with a digit carried by each of said levers, a link connecting each of said levers, an arm carried by said link, a plate provided with a digit carried by said arm 5 and means whereby each of said plates may be moved into alignment with the operative digits of its associated set of wheels when one of the wheels of highest order passes a predetermined point and means whereby said plates may be 10 moved out of alignment with the operative digits of its associated set of wheels.

8. In a machine, a plurality of sets of printing wheels, shafts on which said wheels are mounted, levers pivoted on said shafts, a plate on each of 15 said levers, each of said plates being provided with a numeral, a link connecting said levers, and means whereby one of said levers may be

operated thereby moving its plate, the link, the other lever and its plate so that the two plates will be in alignment with the operative characters of the printing wheels.

9. In a machine, a plurality of sets of printing wheels, shafts on which said wheels are mounted, levers pivoted on said shafts, a plate on each of said levers, each of said plates being provided with a numeral, a link connecting said levers, means whereby one of said levers may be operated thereby moving its plate, the link, the other lever and its plate so that the two plates will be in alignment with the operative characters of the printing wheels and means whereby said levers, link and plates may be reset to 80 85 90 normal position.
